LAUNDRY MACHINE

Edward J. Downes, Albany, N. Y.

Application October 6, 1941, Serial No. 413,723

11 Claims. (Cl. 34—109)

My invention particularly relates to laundry drying machines and similar machines for laundry purposes which comprise a foraminous cylinder rotatably mounted within a casing, the cylinder being adapted to receive articles of a customer's wash which are therein agitated as the cylinder is rotated.

In these machines, the cylinder or drum is provided with an opening through which articles are passed into or taken from the drum and, of course, the casing is provided with an opening and a door therefor arranged to register with the opening in the drum. The drum is provided interiorly thereof with a plurality of pairs of diametrically opposed baffles extending longitudinally of the drum and radially inwardly from the walls thereof. These baffles serve, as the drum is rotated through some suitable driving mechanism, to agitate the articles placed therein, turning them over and over or tumbling them.

Since each customer's wash is processed separately in the cylinder or drum and since washes vary considerably in size, it is of advantage to provide a removable partition element which may be inserted in a cylinder of the above character to subdivide the interior thereof into two compartments whereby two, comparatively small washes could be simultaneously processed.

Broadly speaking, therefore, it is an object of this invention to provide a novel partition element for a machine of the character above pointed out which is provided with means for promoting a highly exposed and distributed condition of the articles in the two compartments of the cylinder formed thereby as the cylinder is rotated.

It is also an object of this invention to provide a partition element particularly designed for use with laundry machines having open-ended cylinders therein, said partition element being adapted to be positioned in cylinder-subdividing relation therein and being provided with means for preventing articles from sliding over the end edge thereof which lies adjacent the open end of the cylinder.

A still further object of my invention resides in providing a cylinder for laundry machines of the above described character which is provided with baffle means so constructed and arranged relative to a partition element within said cylinder as to promote a highly exposed and distributed condition of the articles in the compartments formed by the partition as the cylinder is rotated.

With these and other objects in view, my invention includes the novel elements and the correlation and arrangements thereof described below and illustrated in the accompanying drawings, in which—

Fig. 1 is an elevation view of one form of laundry drying machine embodying my invention;

Fig. 2 is a sectional view thereof taken in about the plane 2—2 of Fig. 1;

Fig. 3 is a transverse sectional view of the cylinder of the machine;

Fig. 4 is a plan view of the partition element of my invention;

Fig. 5 is a sectional view thereof taken in about the plane 5—5 of Fig. 4;

Fig. 6 is an end elevation of the partition element;

Fig. 7 is a fragmentary, enlarged sectional view taken in about the plane 7—7 of Fig. 6 and through one end of the partition and the baffle element secured thereto; and

Fig. 8 is a fragmentary, transverse sectional view of the cylinder showing the partition element operatively mounted therein.

25 In the embodiment of my invention herein illustrated, I have shown a laundry drying machine of the type which is loaded through the end of the casing and cylinder therein, and it will be understood that the disclosure herein presented is illustrative of the elements and the combinations and correlation of the elements of my invention in association with laundry machines of the general character hereinabove pointed out to which my invention relates.

30 Referring to the drawings and first to Figs. 1 to 3, inclusive, I indicates generally a laundry drier comprising a casing 2 having a foraminous cylinder or drum 3 rotatably mounted therein. As shown in Fig. 2, one end plate 4 of the cylinder is provided with an opening 5 therein which

40 registers with an opening 6 in the casing 2. The articles of a customer's laundry are deposited within and taken from the cylinder 3 through the openings 6 and 5 of the casing and cylinder, respectively, and a closure for the opening 6 or a door 7 is mounted on the casing, a suitable latch serving to hold the door in closed position. The other end plate 8 of the cylinder is secured to a supporting and drive shaft 9 journaled in bearings 10.

45 In the type of machine herein illustrated, air is taken in at the top thereof absorbing heat from suitable heating coils, such as steam heated coils, and then passes downwardly through the opening 11 to the cylinder 3. Movement of the heated

air downwardly through the cylinder is promoted by means of a suction device 12 which is mounted in the base of the machine, the air being drawn from the interior of the casing and cylinder through an opening 13 in the bottom of the casing and discharged through a pipe 14. The suction device is operated by an electric motor 15 which also serves to rotate the cylinder 3 through the medium of a suitable speed-reducing mechanism and sprockets 16 and 17 and chain 18.

The cylinder 3 is provided interiorly thereof with a plurality of pairs of diametrically opposed baffles which extend longitudinally of the cylinder and radially inwardly from the sides. In the embodiment herein illustrated, one pair of baffles indicated at 19 are of such radial length that the inner ends thereof project inwardly beyond the edges of the openings 5 and 6 in the cylinder and casing, respectively. The primary purpose of this arrangement, so far as the present invention is concerned, is to enable a partition element of the character hereinafter described to be slid over the ends of said baffles and supported thereon in cylinder-subdividing position. A second pair of such baffles, as indicated at 20 and preferably in quadrature with the baffles 19, are preferably of lesser radial extent than the baffles 19 and extend inwardly from the sides of the cylinder but short of and in spaced relation to the edge of the opening 5 in the cylinder.

In accordance with my invention, the cylinder 3 is provided with a third pair of diametrically opposed baffles indicated at 21. These baffles are preferably disposed adjacent but in circumferentially spaced relation to the baffles 19, as shown, and closer thereto than to the baffles 20. Furthermore, the baffles 21 precede the baffles 19 which they lie adjacent to as the cylinder is rotated. The assumed direction of rotation of cylinder 3 is indicated by the arrow in Fig. 3. In other words, if the cylinder is to be rotated in a clockwise direction in the operation of the machine, the baffles 21 are relatively closely spaced from the baffles 19, which are adapted to support the partition element, in a clockwise direction.

Furthermore, baffles 21 are preferably of lesser radial extent than either of the other pairs of baffles. For example, in a cylinder of a diameter of approximately 36", baffles 20 ordinarily have a radial length of about 4" and I find that excellent results are produced in cylinders of this size when the baffles 21 are about 2" in radial length and when spaced approximately 7" from the adjacent baffle 19.

The baffles 21 when disposed as above set forth serve to promote a highly exposed and distributed condition of the articles as they pass from the sides of the cylinder to the partition element as the cylinder is rotated. In doing this, they prevent the articles especially small articles such as face cloths and the like from rolling up. When rolling and entwining of the articles occurs as compared to a thorough agitation and tumbling of the articles in what may be termed a distributed and opened-up or exposed condition, as the cylinder rotates, the articles take longer to dry and, when dried, are not soft and fluffy as desired. On the other hand, when the baffles 21 are employed, even the smaller articles are maintained substantially continuously in a highly exposed and well distributed condition as the cylinder rotates.

In the absence of these baffles, the articles, especially the smaller ones, have a tendency to slide on the side of the cylinder to the cylinder-

subdividing partition and then across the partition to the opposite side of the cylinder. However, baffles 21 prevent this occurrence, promoting more rapid drying and a much softer and decidedly fluffy condition of the articles.

A preferred form of partition element is shown in Figs. 4 through 8 and in its preferred form, as illustrated, is arranged for use in a machine of the character shown in Figs. 1 and 2 having an open-ended cylinder. The partition indicated generally at 22 is comparatively rigid so that it may be operatively supported on the baffles 19 of the cylinder. In the embodiment shown, the partition comprises a foraminous, plate-like element 23 provided adjacent opposite sides thereof with strips 24 and 25 which cooperatively form a channel of sufficient extent to receive the ends of baffles 19 therein and operatively to support the partition element thereon in cylinder-subdividing position. Adjacent one end thereof, I provide the partition with a baffle element indicated generally at 26 which is adapted to prevent articles from passing over the end edge thereof adjacent the opening in the cylinder, as the cylinder is rotated, and falling into the lower compartment causing confusion of the articles of one wash with those of another.

The baffle element 26 is preferably arranged in upstanding relation to the element 23 and extends outwardly on both sides thereof. The baffle 26 in the embodiment shown is provided along its top and bottom free edges, or the edges thereof extending crosswise of the element 23, with a strip 30 of suitable material, such as felt, for example, which may project for about $\frac{1}{2}$ " beyond the edges of the plate-like elements of the baffle proper. I prefer to provide the baffle 26 with edge strips of this character so as to prevent the arm of an operator from being burned if in reaching into the compartments of the cylinder his arm should engage the baffle. The baffle 26 may be formed as shown in detail in Fig. 7. To the end edge of element 23 is secured a pair of up-standing plates 27 and 28, one on each side of the plate 23. A plate 28 is secured to the plates 27 and 28 preferably adjacent the free edges thereof as shown in order that the rivets or similar securing means employed for this purpose may also serve to fasten in place the overfolded ends of the strips 30 disposed therebetween. These strips, as above indicated, may be of felt or like suitable material which will prevent burning of an operator's arms.

When the partition element 22 is operatively positioned within the cylinder with the end thereof remote from baffle element 26 substantially in engagement with the end wall 8 of the cylinder, the baffle element 26 is designed to lie adjacent the opening 5 in the end of the cylinder whereby to rotate as the cylinder is rotated in closely spaced relation to the door of the casing when closed.

Further in accordance with my invention, I prefer to provide the partition element with baffles extending longitudinally thereof and of the cylinder when arranged therein as indicated at 31. These baffles are disposed one on one side of the partition element and the other on the other side and any suitable means may be employed to secure them to the element. Furthermore, the baffles 31 are preferably disposed adjacent opposite side edges of the partition. For example, assuming the partition is operatively positioned within the cylinder and the

cylinder is designed to rotate in a clockwise direction as indicated by the arrow in Fig. 8 and if the partition is considered as lying in a more or less horizontal plane, the baffle 31 on the upper side of the partition element will lie adjacent the right hand side edge of the partition while the other baffle 31, on the opposite or underside of the partition, will lie adjacent the left hand side edge of the partition. Therefore, as the cylinder rotates in a clockwise direction, the articles will be deposited from the walls of the cylinder upon the partition from whence they will in turn be deposited upon the walls of the cylinder again.

In the absence of baffles 31, the articles may slide off the partition to the cylinder walls causing bunching and rolling thereof. However, the baffles 31 prevent this and promote a more highly exposed and more continuously agitated condition of the articles as the cylinder rotates. In a cylinder about 36" in diameter, the partition element herein disclosed will have an overall width of about 22" and I find that if the baffles 31 are about 2½" high and spaced about 5" from the side edges of the partition that extremely good results are produced.

It will be observed that when the cylinder is subdivided by a partition element and the baffles 21 are provided on the interior of the cylinder in slightly circumferentially spaced relation to the partition and the partition is provided with baffles as illustrated that the articles in both of the compartments so provided will be substantially continuously agitated and thereby maintained in a highly exposed condition whereby not only may the laundering operation be carried out in a shorter period of time but the results will be more satisfactory.

Furthermore the baffle 26 prevents the articles while undergoing such treatment from sliding over the end edge of the partition element and mixing with those of another customer's wash. However ample room for quickly loading and for reaching into the compartments of the cylinder for unloading purposes is provided.

While I have described my invention in its preferred embodiments, it is to be understood that the words which I have used are words of description rather than of limitation. Hence, changes within the purview of the appended claims may be made without departing from the true scope and spirit of my invention in its broader aspects.

What I claim is:

1. In a machine of the character described, the combination with a cylinder open at one end and closed at the other and having radially arranged baffles extending inwardly from the sides thereof, of a foraminous partition element disposed axially of and within said cylinder and extending from adjacent the closed end of said cylinder substantially to the opposite, open end thereof to divide the cylinder into two, separate compartments for containing articles during the operation of said machine, and means disposed adjacent the open end of said cylinder for preventing articles supported on said partition element from sliding over the end edge thereof.

2. In a machine of the character described, the combination with a cylinder open at one end and closed at the other and having radially arranged baffles extending axially of said cylinder and inwardly from the sides thereof in diametrically opposed relation, of a removable foraminous partition element dividing the interior of said

cylinder into two, separate compartments for containing articles during the operation of said machine and comprising means disposed adjacent opposite side edges thereof for engaging diametrically opposed baffles operatively to position said element within said cylinder in cylinder-subdividing relation thereto, said partition element when so operatively positioned extending from adjacent the closed end of said cylinder substantially to the opposite, open end thereof, and means disposed adjacent one end of said element and in upstanding relation thereto and adapted to lie adjacent the open end of said cylinder when said element is operatively positioned within said cylinder for preventing articles supported on said partition element from sliding over the end edge thereof from one compartment formed thereby to the other.

3. In a machine of the character described, the combination with a cylinder open at one end and closed at the other and having radially arranged baffles extending axially of said cylinder and inwardly from the sides thereof in diametrically opposed relation, of a removable, foraminous partition element dividing the interior of said cylinder into two, separate compartments for containing articles during the operation of said machine, said element having channel-shaped means adjacent opposite side edges of said element for slidably engaging diametrically opposed baffles whereby said element may be slid into operative position within said cylinder and in cylinder-subdividing relation thereto, said partition element when so operatively positioned extending from adjacent the closed end of said cylinder substantially to the opposite, open end thereof, and upstanding means adjacent one end of said element and adapted to lie adjacent the open end of said cylinder when said element is operatively positioned therein for preventing articles supported on said partition element from sliding over the end edge of said element.

4. In a machine of the character described, the combination with a cylinder open at one end and having radially arranged baffles extending axially therewith and inwardly from the sides thereof, of a foraminous partition element positioned axially of and within said cylinder in cylinder-subdividing relation thereto, said element extending throughout the length of said cylinder, and a plate upstanding from opposite sides of said element and adjacent an end thereof and lying adjacent the open end of said cylinder; said plate being of sufficient height to prevent articles supported on said partition element from sliding over the end edge of said element while allowing free access to the interior of the cylinder.

5. In a machine of the character described, a rotatably mounted cylinder open at one end and having radially arranged baffles extending axially therewith and inwardly from the sides thereof, means for rotating said cylinder, and a foraminous partition element positioned in axially extending relation within said cylinder and in cylinder-subdividing relation thereto, means adjacent one end of said element and adjacent the open end of said cylinder for preventing articles supported on said partition element from sliding over the end edge of said element, but said means affording free access to the interior of said cylinder, and baffle means on said partition element extending lengthwise of said element and in spaced relation to its side edges for effecting a highly exposed and distributed condition of ar-

ticles within said cylinder as they pass from said partition to the side of said cylinder as it is rotated.

6. In a machine of the character described, a cylinder open at one end, radially arranged baffles extending axially therealong and inwardly from the sides thereof in diametrically opposed relation, a removable, foraminous partition element, means disposed adjacent opposite side edges thereof for engaging diametrically opposed baffles operatively to position said element within said cylinder in cylinder-subdividing relation thereto, and means disposed adjacent one end of said partition element and in upstanding relation thereto and adapted to lie substantially at the open end of said cylinder when said element lies in a cylinder-subdividing position for preventing articles supported on said partition element from sliding over the end edge of said element, but said means affording free access to the interior of said cylinder, and a plurality of baffle means on said element extending lengthwise thereof, one of said baffle means being disposed on one side of said element and another being disposed on the other side of said element.

7. In a laundry machine comprising a casing, a foraminous cylinder rotatably mounted within said casing, means for rotating said cylinder, a plurality of pairs of substantially diametrically opposed baffles extending longitudinally of said cylinder and radially inwardly from the sides thereof, one pair of said baffles being of greater radial length than a second pair thereof and another pair of baffles being of shorter radial length than said second pair and said baffles of greater and shorter radial length being disposed in relatively closer circumferentially spaced relation to each other than to the other baffles.

8. In a laundry machine comprising a casing having an opening in the end thereof, a foraminous cylinder rotatably mounted within said casing and having an opening in the end thereof disposed in registry with the opening in said casing, means for rotating said cylinder, a plurality of pairs of substantially diametrically opposed baffles extending longitudinally of said cylinder and radially inwardly from the sides thereof, a first pair of said baffles extending inwardly beyond the edge of said opening in said cylinder, a partition element for subdividing the interior of said cylinder into two compartments, said element being adapted to pass through the opening in said casing into said cylinder, means adjacent opposite side edges of said partition for engaging said first pair of diametrically opposed baffles to support said partition in cylinder-subdividing relation in said cylinder, and a second pair of said baffles being shorter than said first pair and extending radially inwardly of said cylinder but short of the edge of the said opening therein and lying in relatively close but circumferentially spaced relation to said baffles engaged by said partition element.

9. A laundry machine comprising a casing having an opening therein, a foraminous cylinder rotatably mounted in said casing and having an

opening in one end thereof in substantial registration with the opening in said casing, means for rotating said cylinder, a plurality of pairs of substantially diametrically opposed baffles positioned within said cylinder and extending axially and radially inwardly from the sides thereof, a partition extending between one of said pairs of baffles and substantially from end to end of said cylinder for dividing the interior thereof into two, 10 separate compartments, and means on said partition adjacent the open end of said cylinder and extending transversely of said partition on both sides thereof for preventing articles supported on said partition from sliding over the end edge thereof at the open end of said cylinder; one pair of said baffles lying on opposite sides of said partition and in relatively close relation thereto.

10. In a laundry machine comprising a casing having an opening therein, a foraminous cylinder open at one end rotatably mounted within said casing, means for rotating said cylinder, a plurality of pairs of substantially diametrically opposed baffles extending longitudinally of said cylinder and radially inwardly from the sides thereof, a partition element extending across said cylinder and subdividing the interior thereof into two compartments, means adjacent one end of said partition for preventing articles supported on said partition from sliding over the end edge of said element at the open end of said cylinder and baffle means extending lengthwise of said partition and in spaced relation to the side edges thereof; one pair of the baffles of said cylinder lying on opposite sides of said partition element and in relatively close but circumferentially spaced relation thereto; whereby said last mentioned baffles and the lengthwise extending baffles of said partition are adapted to promote a highly exposed and distributed condition of articles within said cylinder as it is rotated.

11. In a laundry machine comprising a casing having an opening in the end thereof, a foraminous cylinder rotatably mounted within said casing and having an opening in the end thereof disposed in registry with the opening in said casing, means for rotating said cylinder, a plurality of pairs of substantially diametrically opposed baffles extending longitudinally of said cylinder and radially inwardly from the sides thereof, a first pair of said baffles extending inwardly beyond the edge of said opening in said cylinder, a partition element for subdividing the interior of said cylinder into two, separate compartments, said element being adapted to pass through the opening in said casing into said cylinder, means adjacent opposite side edges of said partition for engaging said first pair of diametrically opposed baffles to support said partition in cylinder-subdividing relation in said cylinder, and baffle means upstanding from said partition element and adapted to lie substantially at the open end of said cylinder for preventing articles supported on said partition element from sliding over the end edge thereof.
